UNITED STATES PATENT OFFICE.

KARL HERMANN FRANZ HUTH, OF HAMBURG, GERMANY.

APPARATUS FOR PRODUCING ORNAMENTAL SASH-BARS.

1,074,722.

Specification of Letters Patent.

Patented Oct. 7, 1913.

Application filed October 5, 1911. Serial No. 653,015.

To all whom it may concern:

Be it known that I, KARL HERMANN FRANZ HUTH, a subject of the King of Prussia, and resident of Hamburg, Germany, have invented a new and useful Improvement in Apparatus for Producing Ornamental Sash-Bars, of which the following is a specification.

Lead sash bars, which have an H-shaped cross section and are called by glaziers cames or turned lead are frequently used to connect panes of glass, for artificial glazing, fret-work, stained glass windows and the like. Heretofore, when it was desired to ornament sash bars of this description it was necessary to attach an ornamental strip on the sash bar. According to this invention these two articles are combined by cutting ornamental figurations on the flange of the sash bar, thus forming the bar into an ornamental sash bar itself. To carry out this part of the invention, supporting flat plates or the like preferably of the thickness of the hollow space left in the sash bar are introduced into the grooves and a rotating cutter is made to operate on one or both flanges, thus supported by the plate or the like, the sash bar together with the supporting plates, being held stationary and the cutter being rolled along the sash bar to cut out the desired figuration; or the rotating cutter may be journaled in stationary bearings and the bar together with the supports may be movable. If movable the supporting plates may be made in the shape of disks and provided with means to rotate the same.

In a preferable mode of construction two pairs of cutting disks are mounted on two shafts and intermediate of the same two supporting disks are journaled in such manner that the sash bar is slipped on the same, and the cutting disks operate on the flange, when rotated. The cutting disks and supporting disks are all driven from a common shaft, which may be rotated either by hand or mechanically. The shafts carrying the cutter disks are preferably adjustably journaled to allow for sash bars of different thickness.

In another mode of construction there is only one pair of cutting disks rotatably mounted in a tool similar to a carpenter's plane. The sash bar to be operated on is held by two long plates or rails which partly project with a longitudinal edge into

the grooves of the sash bar and thus support its upper flanges. Means are provided to tighten one rail against the other so as to firmly hold the bar between them, when at the same time supporting its flanges.

Figure 1 of the drawings is a side view partly in section of the preferred construction of an apparatus for producing ornamental sash bars. Fig. 2 is a plan and Fig. 65 3 a front view of the same apparatus. Fig. 4 is a side view of a simplified modification, Fig. 5 a plan and Fig. 6 a cross section of the same. Figs. 7 and 8 show ornamental sash bars made according to this invention. 70

The apparatus shown in Figs. 1 to 3 comprises a frame *a*, which is preferably so shaped as to be adapted to be fastened to a table. Two shafts *b* and *c* are journaled in this frame, and are operatively connected 75 by gear-wheels *d* and *e* of equal diameter and pitch of teeth. At one end of the upper shaft *b* a conical wheel *f* is mounted, meshing with another conical wheel *g*, herein-after more fully described, and the corresponding end of the shaft *c* carries a head *h*. On the face of the head *h* and that of the conical wheel *f* there is a groove *i* crossing the center of the shaft or disk, the purpose of which is hereinafter explained. 80 Contacting with the face of the wheel *f* there is a vertically sliding bracket *k* suitably guided within the frame, and below this bracket and arranged opposite to it there is a second sliding bracket *k*¹ also 85 guided in the frame and contacting with the face of the shaft-head *h*. In each bracket *k* and *k*¹ a shaft *m* is journaled approximately in line with the shafts *b* and *c* respectively and, provided at one end with 90 a head *h*¹ having, similarly to the head *h* and to the conical wheel *f* at its outer face, a groove disposed centrally with regard to the center line of the shaft. Between the heads *h*¹ and *h* or wheel *f* respectively, there 95 is a disk *n* provided at both its faces with a feather *o* fitting in the groove *i* described above. On each disk *n* the feathers on opposite sides thereof are arranged at an angle of 90° to one another. Thus a coupling is 100 constructed permitting the shafts *m* to be rotated by the shafts *b* and *c* though they are not perfectly in line. To raise and lower the brackets *k* and *k*¹ adjusting screws *k*² are provided. 110

On each shaft *m* there is a socket *p* attached, threaded on its outer surface and

carrying two cutting disks q , between which a washer q^1 may be arranged. The disks q are annularly shaped to allow them to be slipped over the socket p , and they are each provided with an inner projection, (not seen in the drawing) projecting into one of a series of slots p^1 in the socket, so as to prevent the cutting disks from rotating on the socket. By the aid of two nuts r the cutting disks q may be adjusted and firmly fastened on the socket. In a plane intermediate of the two pairs of cutting disks two horizontal supports as disks s and s^1 are journaled, the shafts s^2 and s^3 of which are operatively connected with one another by a train of gearing t , t^1 , t^2 , t^3 . These two supporting disks have edges of the thickness of the grooves in the sash bar to be operated upon and are made of soft material such as vulcanite or fiber. The disk s^1 may be detachably secured on its shaft or pivot pin s^3 to enable it to be removed or loosened, for the sake of repairs, or replacing of a disk of different thickness, or for better introducing the sash bar u , should any difficulty arise thereby. The shaft s^2 carries the conical wheel g mentioned above, to transmit rotation when the shaft b is rotated. This shaft b has fixed and loose pulleys w and w^1 to enable it to be driven by mechanical power, and the end x of the shaft b is squared or otherwise adapted to be driven by hand by the aid of a hand crank or hand wheel not shown in the drawing that may be placed on the said squared end in a well known manner. Of course if desired only one of the driving means may be provided for.

From the foregoing it will be well understood that if a sash bar u is introduced in the manner as shown in Fig. 1 and the apparatus is set to work by rotating the shaft b the disks s and s^1 will draw the sash bar through the machine and the knives will cut the flanges of the turned lead or sash bar so as to give the edges the configuration incident to the shape of the cutting disks.

As a rule it will not be necessary to use both pairs of cutting disks. Frequently it will be required to have sash bar ornamentations only on one side of the window. In this case one pair of cutting disks preferably the lower ones will be removed. The apparatus will then turn out sash bars ornamented only on one side, as is shown in Fig. 7. Even only one single cutter may be used, so as to produce a sash bar, of which only one of the four flanges is ornamenteally cut out.

For enabling the removing and replacing of the cutting disks, the front part y of the brackets h h^1 is not integral with the other parts but merely fastened by the aid of the known thumb screw z . The shafts m are journaled in a slot y^1 opening out laterally

to the part y . After loosening the screw z the part y may be turned to one side and the disks q removed by unscrewing the nuts r .

There is no limit as to ornamental designs available for this purpose, and neither is it necessary to arrange the cutters symmetrically as to their figuration. If for instance in the machine shown the right hand cutters are turned at an angle of 60° they will produce an ornamental bar such as shown in Fig. 8.

The thickness of sash bars varies. For this or other reasons the cutting disks may be adjusted as to height, which is done by lowering or raising the brackets h and h^1 as described above.

If sash bars are to be produced, that are ornamented only on one side as shown in Fig. 7, the apparatus shown in Figs. 4-6 may be used with advantage.

On a long block or board 1 suitably shaped are mounted the bar supports which consist of a rail 2 fastened on the board, opposite second rail 3 which is detachably or removably and adjustably arranged. This rail 3 is fastened to a bar 4, which may be screwed or otherwise pressed against the projecting body of the block 1 for instance by the lever 5, so as to firmly hold a sash-bar u on the rails 2 and 3. On the device so far described an implement 6 similar to a carpenter's plane is placed, consisting of a frame having a back-handle 7 and a front handle 8. Within this frame which has flanges 9 reaching over the rails 2 and 3 a screw pin 10 is fastened serving as an axle for a socket 11. This socket is constructed similar to the socket p hereinbefore described, with cutting disks, fastening nuts 105 and a washer.

It will be well understood that if the implement 6 is gripped by the hands similar to a carpenter's plane and moved along the rails 2 and 3, the cutting disks can be rolled along the sash bar and will give the upper flanges the desired ornamentation. It is evident that also in this apparatus only one cutting disk may be used if desired.

It need scarcely be pointed out that the two examples illustrated and described above may be replaced by apparatus of various constructions to carry out the present invention.

What I claim is:

1. An apparatus for ornamenting sash bars of lead comprising two supporting disks mounted opposite one another in the same plane and adapted to project into the grooves of the sash bar in operation, a train of gears connecting the said disks and to rotate the same, two parallel shafts, one above and the other below the said disks, two pairs of ornamenting cutting disks each pair mounted on one of the shafts, gears to 125

operatively connect the shafts and means to rotate one of the shafts.

2. An apparatus for ornamenting sash bars of lead comprising a frame, two supporting disks mounted rotatively opposite one another in the same plane at such a distance apart as to allow a sash bar to be slipped on the disks, where they meet, a train of gears connecting the disks, two shafts carrying each a pair of cutting disks and adapted to be adjusted relatively to the sash bar held by the supporting disks, and means to rotate the disk.

3. An apparatus for ornamenting sash bars of lead comprising a frame, two parallel shafts journaled in the frame, two pairs of cutting disks mounted on the shafts, means to rotate the shafts two supporting disks rotatably mounted in a plane intermediate of the two shafts, gearings between the two supporting disks and gearings be-

tween one of the supporting disks and one of the shafts.

4. An apparatus for ornamenting sash bars of lead comprising a frame, two sectional parallel shafts journaled in the frame, a coupling between the sections of the shafts adapted to transmit rotation, even though one section be out of line with the other, adjustable bearings for one section of each shaft, a pair of cutting disks mounted on the adjustable section of each shaft, two supporting disks rotatably mounted in a plane intermediate of the two shafts, means to rotate the shafts carrying the cutting disks and means operatively connected with the shafts to rotate the supporting disks.
